UNITED STATES PATENT OFFICE.

MEYER S. HESS, OF BALTIMORE, MARYLAND.

SHOE.

1,354,972.

Specification of Letters Patent.

Patented Oct. 5, 1920.

Application filed April 20, 1918. Serial No. 229,767.

To all whom it may concern:

Be it known that I, MEYER S. HESS, a citizen of the United States of America, residing at Baltimore city, in the State of Maryland, have invented new and useful Improvements in Shoes, of which the following is a specification.

The object of the invention is to provide a shoe construction and method of producing the same, as applied particularly to welt shoes, by which, even with the use of an inferior grade of leather, for the insole a superior grade of the product, in matters of strength, durability and finish, is assured; to provide means for reinforcing or fortifying the main insole rib to which the welt and upper are secured; to provide means for positively anchoring the marginal edge or feather of the insole; to provide means for definitely positioning and restraining the feather of the insole to prevent curling; and to provide means to render the sole elements mutually reinforcing while permitting a sufficient latitude of movement longitudinally of the shoe to allow for flexibility in walking, without producing strains tending to transversely disarrange, or disturb the described and approved relative positions of these or any other elements of the structure. In the drawing, representing a preferred embodiment of the invention, it being understood however that changes in form, proportions and details of construction and arrangement may be resorted to within the scope of the appended claims,

Figure 1 is a transverse sectional view of a shoe embodying the features of the invention.

Fig. 2 is a bottom plan view showing the insole with the reinforcing web attached but prior to the attaching of the upper end welt and the trimming of the rib for the reception of the outer sole.

Fig. 3 is a transverse sectional view of an insole reinforced according to the plan shown in Fig. 1 but showing the same prior to the attachment of the other parts forming a shoe; and

Fig. 4 is a transverse sectional view of another form of reinforced insole.

Essentially the shoe embodying the invention includes the usual elements, namely the upper 36, the outer sole 38, the insole 30 and the welt 37, the insole being provided with the usual marginal rib 31 formed by

cutting webs of material from the body of the insole to leave a reduced marginal feather 32, and the welt being attached to the insole by means of a line of stitching 39 which passes through the material of the upper, interposed between said welt and rib and holds the constituent elements of the rib in contact as an anchor for the upper and the outer sole which is attached to the welt by a line of stitching shown at 41.

Associated with the above noted elements is a reinforcing member consisting of a flexible strip 33 which may consist of fabric such as canvas which extends around the margin of the shoe and is at its edges or marginal portions permanently and securely anchored to the insole. The attachment of the reinforcing strip is preferably in the manner shown, a line of stitching 34 being employed and the strip being carried around the feather 32. At the opposite marginal edge, the reinforcing strip or web is positively and securely anchored to the insole in contact with the lower surface thereof by a line of stitching 35 identical with the stitching 34. Thus one marginal edge of the reinforcing strip or web is permanently secured or anchored to the top surface of the insole and the opposite marginal edge is secured or anchored positively to the under surface of the insole on an intermediate line of the latter within the space bounded by the insole rib, and intermediate said reinforcing strip or web extends around or embraces the feather of the insole, with whose upper and lower surfaces it is in contact, and extends across or spans the insole rib 31 so as, primarily, to occupy a position substantially as indicated in Fig. 3 wherein the portions of the strip or web on either side of the plane of the rib occupy the positions of chords or represent hypotenuses of triangles whose legs are represented by the side surfaces of the rib and the plane of the under surface of the primary insole. More or less transverse strain or tension may be applied to the reinforcing strip or web at the time of anchoring its marginal edges respectively to the insole structure, but under no circumstances should the relation of the parts at this stage in the construction of the shoe be such that there is insufficient transverse slack in the strip or web to permit the portions thereof at the opposite sides

of the plane of the insole rib to lie out of contact with the side surfaces of said rib. In applying the welt between which and the rib there is interposed the edge of the upper, the welt securing stitches are extended not only through the welt, upper and rib, as in the ordinary practice, but also through both of said side portions of the reinforcing strip or web, and the tightening of these stitches obviously will draw said side portions of the strip or web toward the planes of the side surface of the rib, to produce an angular form approximating the angles between the sides of the rib and the plane of the insole, as shown by the dotted lines in Fig. 3, and the effect of this operation will be to place the reinforcing strip or web under a more or less severe tension, so that the portion between the rib and the inside line of anchoring stitches 35 and the portion between said rib and the marginal edge of the insole are placed under tension so that the rib is reinforced against strains by the inner portion of the strip or web shown at 33^a and against inward strain by the portion of the strip or web indicated at 33^b, and the feather of the insole is positively anchored or bound by the embracing portion of the strip or web to counteract any tendency of said feather, even after protracted use of the shoe, to curl or turn upward. The rib thus acts as a reinforcing element to the feather edge of the insole, and this relation of reinforcement is maintained even if, after the parts have been secured as described, the lower edge portion of the rib, with the portion of the strip or web should be removed or cut away, as is common in the construction of shoes of this type, in order to reduce the projection of the rib from the plane of the under surface of the insole. In other words, the trimming of the rib at its lower edge, after the welt has been secured in place by the line of stitching represented at 39 will not affect the described relation of the elements including the transversely tensioned condition of the portions of the strip or web which extend in opposite directions from the rib toward the marginal edges which are anchored securely to the insole structure.

It has been found in practice that particularly when an inferior grade of insole leather is used, the attachment of reinforcing means to the outer surface thereof has been more or less insecure with the result that after a time the connection between the parts is destroyed or impaired with the result that the insole rib is subjected to transverse strains which it is incapable, by reason of the quality of the material, to withstand, and hence there is a resulting disarrangement of the elements of the shoe or a tearing apart of the outer sole and insole or of the

upper and the insole, and moreover under the present practice, the unsecured or relatively unrestrained condition of the feather of the insole permits an upward displacement or curling thereof which materially detracts from the comfort and durability of the shoe, whereas by the arrangement above described these disadvantages are eliminated and the related parts are bound together under such conditions as to retain them in their original relations and to substantially increase the durability of the structure. 70

As a means of rendering the joint between the upper and sole water-proof the reinforcing strip or web may be coated or saturated with a water-proof material or may be rubberized, but it is even more important, owing to the fact that the strip or web is transversely tensioned and should be maintained permanently under a relatively high tension, 80 that the strip or web while flexible should be transversely inelastic so as to avoid any tendency to lateral yield which would permit of the relative disarrangement of the parts or the imposition of transverse strains 85 upon the insole rib. On the other hand, in order that the shoe be longitudinally flexible, to permit its bending freely as in walking, said reinforcing strip or web should be longitudinally elastic to a degree sufficient 90 to permit it to give with the movements of the parts to which it is secured without applying such a strain as would tend to break or injure the connections and thus destroy the co-operative relation which is essential 95 to protracted efficiency. 100

The construction set forth in Fig. 3 is identical with that shown in Fig. 1 with the exception that the reinforcing strip 33 is anchored on the under edge of the feather 105 by the stitching 40, as illustrated, and is shown completely surrounding the rib, as it appears prior to the trimming of the rib.

The modified structure of insole 42 shown in Fig. 4 is provided with a reinforcing web 43 which completely surrounds its body portion, marginal rib and feather, practically, forming an envelop for the insole. The free edges of this web are joined together and connected to the insole by a line of 110 stitching 45 which extends completely through the insole, the web on top of the insole, and the connecting edges of the web below the insole. It will be observed that the connecting edges of the web overlap. 115 This is thought to be preferable to abutting edges, although abutting edges can be effectively joined together and secured to the insole by a form of stitch commonly known as the surgical stitch. 120

Since both the insole shown in Fig. 3 and that shown in Fig. 4 are illustrated as they appear prior to the attachment of the upper and welt, the reinforcing webs of both are not shown under tension, the tensioning be- 130

ing accomplished when the uppers and welts are sewed on, as has been clearly set forth hereinbefore.

It is obvious from the foregoing description that the application of the reinforcing member in the construction of the shoe can be accomplished without substantially increasing the operations of building the shoe, and hence without adding appreciably to 10 the cost of manufacture thereof.

What is claimed is:—

1. A shoe construction embodying an insole having a marginal rib, a welt and a line of stitching connecting the welt to the rib, 15 and a reinforcing strip marginally anchored on either side of and spanning said rib, and transversely tensioned by said line of stitching.

2. A shoe having an insole provided with 20 a marginal rib and welt, a flexible reinforcing strip extending from the rib around the feather to the upper side of the insole and a connection between said rib and said welt transversely tensioning said reinforcing strip.

25 3. A shoe having an insole provided with a marginal rib, a flexible reinforcing strip marginally anchored on opposite sides of

the plane of the rib, and stitching attaching the strip to the rib and maintaining the 30 strip under tension transversely of the rib.

4. A shoe having an insole provided with a marginal rib, a flexible reinforcing strip marginally anchored on opposite sides of the plane of the rib and intermediately spanning 35 the latter, and stitching intermediately attaching the strip to the rib and maintaining the former under tension on opposite sides of the latter.

5. A welt shoe having an insole, provided 40 with a marginal rib, and a reinforcement consisting of a flexible, transversely tensioned strip marginally stitched to said insole in spanning relation with said rib and intermediately secured to the rib by a line 45 of stitching transversely engaging the latter.

6. A shoe construction embodying an insole having a marginal rib, a welt and a line of stitching connecting the welt to the rib, and a reinforcing strip marginally anchored on either side of and spanning said rib, and transversely tensioned on both sides 50 of the rib by said line of stitching.

In testimony whereof I affix my signature.

MEYER S. HESS.
